CLAIM

We claim the ornamental design for a flexible garment for supporting a small portable electronic device, as shown and described.

DESCRIPTION

FIG. 1 is a front view showing our new design that includes a transparent pocket portion for containing a small portable electronic device;

FIG. 2 is a left side view thereof;

FIG. 3 is a rear view thereof, with a strap portion thereof removed to indicate indefinite length;

FIG. 4 is a right side view thereof;

FIG. 5 is a top view thereof; and,

FIG. 6 is a bottom view thereof.

Portions broken away or not shown form no part of the claimed design. No appearance feature of any part of the garment located behind a transparent window shown in FIG. 1 is claimed.

Because garments embodying features of the present invention are flexible, those skilled in the art will appreciate that configuration exhibited by the garment is likely to vary depending, at least in part, on how the garment is worn, positioned or supported.
